(57) CLAIM

The ornamental design for a garment, as shown and described.

DESCRIPTION

FIG. 1 is a front perspective view of a garment in accordance with the present invention.

FIG. 2 is a front view thereof.

FIG. 3 is a right side view thereof.

FIG. 4 is a left side view thereof; and,

FIG. 5 is a top rear perspective view thereof.

The cross-hatch shading is fragmentally shown for convenience of illustration; it being understood that the cross-hatch shading is uniformly continued over the surface on which it appears.

The lighter dashed lines having equal length segments in the figures show portions of the foldable garment which form no part of the claimed design. The darker dashed lines having equal length segments in FIG. 1 showing a wearer illustrate environmental structure and form no part of the claimed design.

The short-short-long broken line shows a portion of the garment that forms a part of the claimed design.
